UNITED STATES PATENT OFFICE.

ALBERT VAUPEL, OF BERLIN-GRUNEWALD, GERMANY, ASSIGNOR TO WESTINGHOUSE ELECTRIC & MANUFACTURING COMPANY, A CORPORATION OF PENNSYLVANIA.

CONDUCTOR HANGER.

Application filed October 28, 1926, Serial No. 144,769, and in Germany November 21, 1925.

My invention relates to conductor hangers and particularly to hangers for suspending high-voltage transmission-line conductors.

One object of my invention is to provide a device of the above-indicated character that shall be simple and durable in construction, economical to manufacture and effective in its operation.

Another object of my invention is to provide a transmission-line hanger that shall be free of small loose parts, such as nuts and bolts, and that shall thereby greatly facilitate its installation.

A further object of my invention is to provide a hanger of the tongs or "come-along" type that shall embody a single pivot member.

Heretofore, a transmission-line hanger of the tongs or pivoted-link type has embodied a plurality of links and pivot pins rendering the device expensive and difficult to manufacture, as well as difficult to install.

Accordingly, it is my aim to overcome these objections and to simplify the device by reducing the number of parts and providing a single pivot connection therefor.

Figure 1 of the accompanying drawings is a side elevational view of a hanger constructed in accordance with my invention, portions being broken away for clearness and the several elements thereof being disposed in open relation for receiving a conductor.

Fig. 2 is a view, similar to Fig. 1, of the device shown therein but with the conductor in position and the device in its closed or clamping position, and

Fig. 3 is a view, similar to Fig. 2, of a modified form of my invention.

The device comprises, in general, a conductor-supporting member 1, clamping members 2 and 3, and a hanger member 4 for effecting the clamping action of the members 2 and 3 and supporting the hanger, as a whole, from a high-voltage insulator or similar structure.

The member 1 has a portion 5, preferably of slightly curved channel-shape, having one of its sides 7 projecting upwardly therefrom and provided with an opening for the reception of a pivot pin 8.

Each of the arms 2 and 3 comprises a clamping portion 9 having a slightly curved clamping surface 10 substantially conforming to the curvature of the channeled portion 5, an arm portion 12 and an outwardly

extending hook portion 14 at the outer end of the arm 12.

The hanger member 4 comprises an eye or other portion 15 for attaching the device to a suspension insulator, in a usual and well-known manner, and a portion 16 having a slot or aperture 17 therein, whereby the member 4 may embrace the arms 12.

In operation, with the parts related as shown in Fig. 1, a conductor 18, as shown in Fig. 2, is placed in the channel portion 5, after which the member 4 is moved away from the member 1 to move the arms 12 toward each other about the pin 8 and to move the clamping surfaces 10 against the conductor 18. This movement may be effected during the installation of the device by placing a hook in the eye 15 to raise the clamp to operative position on an insulating tower or similar structure.

As shown in Fig. 2, the device depends, for its clamping action, upon the weight of the conductor 18 and is prevented from release from its supported position by the hook portions 14 on the arms 12.

In the modification of my invention shown in Fig. 3, in which corresponding parts are designated by corresponding reference characters, the construction is substantially the same with the exception that a screw bolt 20 or other means is provided which cooperates between the members 1 and 4 to effect a permanent lock between the parts.

While I have shown and described particular forms of my invention, changes may be effected therein without departing from the spirit and scope thereof, as set forth in the appended claims.

I claim as my invention:

1. A conductor hanger comprising a conductor-supporting clamp-jaw member, pivoted clamp-jaw members having a single pivotal connection to said supporting jaw member and a suspension member cooperating with said pivoted members to effect the clamping action.

2. A conductor hanger comprising a member having a channel for the reception of a conductor and a pivot, clamp members mounted on said pivot adjacent to said channel and a suspension member for supporting and actuating said pivoted members about the pivot thereof to clamping positions and holding them therein.

3. A conductor hanger comprising a

conductor-supporting clamp-jaw member, a pair of crossed movable clamp-jaw members mounted on said supporting member by means of a single pivot and means for actuating and fastening said movable clamping members.

4. A conductor hanger comprising a conductor-supporting clamp member, a pair of movable clamp members including crossed arms having a single pivotal connection to said supporting member, and a suspension member cooperating with the outer portions of said arms to effect clamping action between said members.
15. 5. A conductor hanger comprising a channeled conductor-supporting clamp member having a pivot-supporting portion, a pair of crossed clamp members pivoted to said portion and having clamping portions to engage 20. the conductor and diverging outer arm portions, and a suspension member embracing said outer arm portions, the clamping action being effected by relative movement between said outer arms and said suspension member.
25. 6. A conductor hanger comprising a channeled clamp member for supporting the conductor and having a pivot-supporting portion, a pair of crossed clamp members pivoted to said portion and having clamp portions on 30. opposite sides of the pivot for engaging the

conductor in the channel and diverging outer arms, said arms having hook portions, and a suspension member embracing said arms inside said hook portions.

7. A conductor hanger comprising a channeled clamp member for supporting the conductor and having a pivot-supporting portion, a pair of crossed clamp members pivoted to said portion and having clamp portions on opposite sides of the pivot for engaging the 40 conductor in the channel and diverging outer arm portions, a suspension member embracing said outer arm portions, and means for locking the suspension member relative to the channeled member.

8. A conductor hanger comprising co-operating relatively-movable clamp-jaw members including a pair of crossed pivoted arms, and a member co-operating with said arms outside the pivot position thereof for supporting said first members and causing clamping relative movement thereof, said first members including means for preventing separation of the clamping members from the supporting member.

In testimony whereof, I have hereunto subscribed my name this 5th day of October, 1926.

ALBERT VAUPEL.
